UNITED STATES PATENT OFFICE

ALBERT MOSHEIM, OF NEW YORK, N. Y.

DESIGN FOR A CAKE OF SOAP

Application filed October 16, 1929. Serial No. 33,053. Term of patent 14 years.

To all whom it may concern:

Be it known that I, ALBERT MOSHEIM, a citizen of the United States, and a resident of New York, in the county of New York and State of New York, have invented a new, original, and ornamental Design for a Cake of Soap, of which the following is a specification, reference being had to the accompanying drawing, forming part thereof.

I claim:

The ornamental design for a cake of soap, as shown.

Des Moines, Iowa, September 24, 1929.

ALBERT MOSHEIM.
